CLAIM

I claim the ornamental design for a lift chair with swivel and slide feature, as shown and described.

DESCRIPTION

FIG. 1 is a perspective view of a lift chair with swivel and slide feature showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a bottom plan view thereof, showing the base mechanism in a rotated position;

FIG. 9 is a bottom plan view thereof, showing the base mechanism in a rotated and slid position;

FIG. 10 is a bottom plan view thereof, showing the base mechanism in a slid position;

FIG. 11 is an additional perspective view thereof, showing the seat cushion in a lifted position;

FIG. 12 is a perspective view of an additional embodiment thereof; and,

FIG. 13 is a perspective view of an additional embodiment thereof, showing the seat cushion of this embodiment in a lifted position.

The broken lines in the drawings are for illustrating environmental structure only and form no part of the claimed design.
